CABINET FOR AN INPUT-OUTPUT DEVICE FOR A DATA HANDLING SYSTEM

John R. Bittner and Kenneth C. McCartney, Waynesboro, Va., and Gregory F. Fossella, Marshfield, Mass., assignors to General Electric Company, Waynesboro, Va.

Filed Apr. 8, 1974, Ser. No. 458,563

Term of patent 14 years

Int. Cl. D14—02

U.S. Cl. D64—11 C

FIG.1.

FIG.2.

FIG.3.

FIG.4.

FIG.5.

FIG. 1 is a perspective view of a cabinet for an input-output device for a data handling system, showing our new design;

FIG. 2 is a top plan view

FIG. 3 is a right side elevational view;

FIG. 4 is a left side elevational view; and

FIG. 5 is a rear perspective view.

We claim:

The ornamental design for a cabinet for an input-output device for a data handling system, substantially as shown and described.
